TOTALIZER FOR COUNTING MACHINES

Anton Van Veen, West Hartford, Conn., assignor
to The Denominator Company, New York,
N. Y., a corporation of New York

Application August 19, 1936, Serial No. 96,786

4 Claims. (Cl. 235—117)

This invention relates to a device, such as a totalizing counter, for indicating the total of the numbers registered upon counting machines which comprise a plurality of individual counters.

5 In such counting machines, it is common to employ a series of independent counters which are grouped together to form a unit, or bank, and on each of which counters may be registered the number of one particular kind of an article 10 or value.

Such counting machines are particularly adapted for use in restaurants or in any other case where different articles are handled or produced and where it is desired to have an accurate 15 count of each item for the purpose of knowing exactly how many of each of said articles have been handled.

The object, therefore, of my invention, is to provide a totalizing counter which may be embodied as a part of a counting machine and which will register the total of all the numbers registered on the individual counters of said machine.

A further object of my invention is to provide such a totalizing counter which is of a construction substantially similar to that of the other counters used in said machines, in order that the same may be produced and incorporated 25 in said machine without requiring special parts or tools.

A further object is to provide a totalizing counter which can be connected readily to a machine comprising a plurality of units, or banks, of said individual counters so that a single totalizing counter will register the total of all of the numbers on the counters incorporated in all 30 of the units comprising said machine.

Further objects will be clearly understood from the following description and from the drawings 35 in which:

Figure 1 is a plan view illustrating a counting machine comprising my invention.

Figure 2 is a front view in elevation thereof.

40 Figure 3 is an end view thereof.

Figure 4 is a plan view on an enlarged scale and partly in section on line 4—4 of Figure 3.

Figure 5 is an end view in section on line 5—5 of Figure 4.

Figure 6 is an end view in section on line 6—6 of Figure 4.

Figure 7 is a fragmental view illustrating a modification in the construction of the totalizing counter.

Figure 8 is a similar view showing a further 45 modification.

Figure 9 is a side view in elevation showing my invention as applied to a machine comprising a plurality of units, or banks, of individual counters.

As illustrated in the drawings, the numeral 5 denotes a counting machine comprising a single unit composed of a series of counters 6. These counters are of a common form of construction and, therefore, are not illustrated in detail. Each of said counters, however, comprises a base 7 on which is mounted a series of registering wheels 8 having numbers 9 marked on the periphery thereof. The said wheels operate to show, through a window 10, the number of times the push button 11 is operated to register a single 15 item. The mechanism for operating the wheels 8 includes a lever 12 to which the push button 11 is mounted. The lever is provided with a gear portion 13 which meshes with a pinion segment 14 comprising the actuating member 15. The 20 said member 15 is mounted on a shaft 16 which is supported in suitable bearings on the base 7 and has, connected therewith, an operating pawl 17 which engages ratchet teeth 18 that project sidewise from the outside registering wheel 8. 25

The operation of said counters, as now commonly constructed, is as follows:

When the lever 12 is rocked on its shaft 19 by an operator pressing down on the button 11, the gear 13 will rotate the member 15 on the 30 shaft 16 and actuate with it the pawl 17 in a clockwise direction. The rear end 20—a of the projection 20, illustrated in dotted lines in Figure 5, will then engage the side 18—a of the tooth 18 which is in operating relation therewith 35 and rotate the first, or units, wheel in a counter-clockwise direction for one half of the distance between the said teeth. When the said push button is released, the member 15 will be rocked back in a counter-clockwise direction by the 40 spring 22. The forward end 20—b of the projection will then engage the side 18—b of the correspondingly opposite tooth 18 and turn the units wheel for the other half of the distance between the teeth. The said member 15 will 45 then come to a stop in the position shown in Figure 5, thus positioning, under the window 10, the next higher number on the periphery of the said wheel. The spring 22 acts to return to and retain the lever 12, the member 15 and pawl 17 50 in their normal position, as illustrated in the drawings, in which position the extension 20 will rest within the spacing 23, between the teeth 18, and hold the said registering wheels in their indicating position.

It is to be understood that, in each of the individual counters shown, there are three wheels provided which will allow a registration of three figures or, in other words, up to 999. Any number of wheels may be used, however, in accordance with requirements. It is also to be understood that the wheel operated by the pawl registers single digits. The second wheel registers ten digits, and the third, one hundred digits. In other words, the single digit wheel makes one-tenth of a revolution for each operation of the push button. The second wheel makes one-tenth of a turn for each revolution of the second wheel, or for each one-hundredth operation of the push button.

I have illustrated in the drawings only that portion of the registering mechanism which is related to my invention. The same consisting of the mechanism for operating the unit wheel of each counter. The mechanism for operating the higher order wheels through the operation of the unit wheel is not shown, however, as the same is not a part of my present invention and may be of any form such as commonly used in the type of counters illustrated and as well understood by those skilled in the art.

As may be clearly seen from the illustration in Figure 4 of the drawings, each of said counters is a self-contained unit and comprises a main shaft 24 on which the said registering wheels are mounted. The said shaft is provided with an extension 25 at one end and a notch 26 at its opposite end. The counters may be joined together side by side to form a unit, or bank, and secured together between end plates 27 and 28 by means of tie-rods 29. When thus joined, the main shaft 24 of each counter is joined to the main shaft of the next counter by means of the said projections and notches in said shaft. A re-set knob 30 is mounted in the end plate 27 and has a stud 31 with a notch for receiving the projection 25 on the main shaft of the counter adjoining the said end plate. Each of the counters comprises a suitable resetting mechanism operable by rotation of the main shaft thereof but not shown and are thus joined together so that when it is desired to re-set said counters to zero, all of them may be quickly and simultaneously re-set by the operation of the knob 30.

From the above description it will be understood, that my improved counting machine comprises a series of individual counters which are joined in tandem and which may consist of any number of said counters desired. For instance, where the said machine is used in a restaurant to register the number of meals that are served, a counter is provided in the machine for each kind of a meal. In such cases, each counter in the machine is provided with a tag on the front indicating the name of the meal such as steaks, pot roasts, etc. When a meal is served, the operator will press the push button on the counter designated for that particular meal and thus register the same thereon so that the machine will show at all times just how many meals of each kind have been served.

In the form of such counting machines heretofore used, it has been necessary to add the number showing on each counter in order to determine the total number of all the meals sold during a certain period. By my invention, I provide a totalizing counter or, separate counter in each machine for registering the said total in the following manner: In accordance with my invention, the member 15 in each of the counters

is provided at one end with an operating boss 31. A totalizing operating shaft 32 is mounted in suitable bearings in each of said counters and extends through all of the counters contained in each unit as clearly illustrated in Figure 4. The said shaft is positioned between the end plates 27 and 28. A lever 33 is contained in each of said counters and splined to said shaft. A totalizing counter 34, which is substantially similar in construction to the individual counters above described, is provided in said unit. In the said totalizing counter, however, there are four of the registering wheels preferably provided as the said counter may be required to register a total of four figures. The lever 12-a is cut off, as clearly illustrated in Figure 6, and the lever 33a, which is similar to the other levers 33, is reversed on the shaft 32 in its relation to the operating boss 31 on the member 15 of said totalizing counter.

The main shaft 35, of the totalizing counter, is preferably connected with the main shaft 24 of the other counters in the same unit. The said main shaft 35, however, may be disconnected from the shaft 24 of the other counters so that the totalizing counter can be reset independently of the other counters. If desired, the shaft 35 in the totalizing counter may be constructed as shown in the modification illustrated in Figure 7 of the drawings, so that it may be set in either a disengaged or engaged position with relation to the shaft of the adjoining individual counter. In this construction, the said main shaft is slidably mounted in its bearings and provided with a re-set knob 36 so that the said shaft may be pulled outwardly, to the position shown, to permit independent re-setting of said counter. A stop washer 37, or other suitable means, may be provided on said shaft for limiting the sliding movement thereof by its engagement with the end plate 28 or with the casing of said counter. In this construction, when it is desired to cause the said individual counters to be re-set simultaneously with the totalizing counter in the same unit, the said shaft 35 may be engaged with the shaft 24 of the individual counter by forcing the re-set knob 36 inwardly and causing the extension 25 on said shaft to engage the notch 26 in the adjoining shaft.

As shown in the modification illustrated in Figure 8 of the drawings, the end of the shaft 35 adjoining the end of the individual counter may be plain so that it will be at all times independent thereof and the outer end of the said shaft 35 may extend into an opening 38 in the end plate 28 and have a notch 39 to provide means whereby the said main shaft 35 may be engaged by a key, or other suitable means, inserted through the opening 38, for turning the said shaft when it is desired to re-set the totalizing counter.

It will be understood that the said totalizing counter is included as an extra counter in the counting machine and that the same may be so constructed that it can be re-set individually, or connected thereto so that it may be re-set simultaneously with the individual counters. Regardless of whether the said totalizing counter is connected or disconnected from the other counters, as far as the re-setting operation is concerned, it is always so connected to each individual counter, that when any one of said individual counters are operated the said operation thereof will also operate the said totalizing counter and thereby cause to be registered, on said totalizing counter, the total of all of the numbers

showing on all of the individual counters contained in the entire machine. The said totalizing counter will, therefore, show, at all times, the number of operations applied to the individual counters during a certain period. In some instances, however, as when the totalizing counter is re-set individually, the number showing on said counter may represent the total of operations performed on all of the individual counters 10 during a certain period and not the total of the numbers showing, thereon, as they may have been retained there for some desired purpose.

The operation of my improved totalizing counter is as follows:—

15 When one of the individual counters is operated in its normal manner, the member 15 will be rocked by the operation of the lever 12, as hereinabove described, and the boss 31 will be moved downwardly, operating the lever 33 and 20 rotating the shaft 32 in a contra-clockwise direction.

The rotation of said shaft will rotate the lever 33a which will force downwardly the boss 31 on the totalizing counter associated therewith, 25 turning the member 15 and therethrough operating the pawl 17 in exactly the same manner as the said pawl 17 is operated through the levers 12 in the individual counters. In the said totalizing counter, the portion 12—a of the lever 12 is used merely to apply, the action of the spring 22 therethrough for returning the member 15 and pawl 17 to their normal positions.

In the modification illustrated in Figure 9 of the drawings, a single totalizing counter, which 35 is made in accordance with my invention, may be used to register the total of all the individual counters contained in a machine comprising a plurality of units or banks. These units may be used and mounted on a frame forming a base 40 such as 40, and each unit may consist of any number of individual counters desired. In such a machine, the shaft 32 on each unit extends through the end of the plate 28 thereof and has mounted thereto an operating lever 41 which is 45 in reversed position with relation to the levers 33 in each of the individual counters.

My improved totalizing counter 34 may be mounted in said machine in any position desired but preferably at the end of the top one of said 50 units in the same manner as in a machine comprising a single unit as above described. A lever 41—a is connected to the end of the shaft 32 of said unit in a reversed position to that of the levers 41. A slide bar 42 is mounted upon studs 55 43 which are secured to the ends of the units and project through slots 44 in said bar. Studs 45 are provided in said slide bar in operating relation with each other of the operating levers 41 and 41—a.

60 In the modification illustrated, when any one of the individual counters of a unit is operated, the operation thereof will rock the shaft 32, in that particular unit, and the lever 41 associated therewith will slide the bar 42 so that it will 65 rock the lever 41—a, on the shaft 32 of the unit containing the totalizing counter, in a contra-clockwise direction, and cause it to rock the said shaft 32 in the same manner as above described in a single unit.

70 It will be clearly seen that the totalizing counter may be mounted at any position within a unit of individual counters and still operate as described. It will also be seen that, by my invention, I have provided a totalizing counter 75 which can be produced by a simple modification

of a standard form of a counter. I have also provided means whereby, by simply connecting the said totalizing counter with a unit or bank of individual counters, each operation on any of said individual counters will be registered on the 5 said totalizing counter.

I have described and illustrated one form of counters to which my invention is adapted. It is to be understood, however, that my invention may be used, without departing from the scope thereof, in combination with various other types and forms of counters where it is desired to register, upon a single separate counter, the total of all of the numbers registered upon a plurality of individual counters.

I claim:

1. A counting machine of the character described comprising a plurality of individual counters and a totalizing counter; each of said counters having a units wheel, a plurality of teeth 20 associated with said wheel, a pawl adapted to turn said wheel for the distance of one tooth by engagement with said teeth during a cycle of operation of said pawl, a manually operated member for operating said pawl, a rocker shaft extending through all of said individual counters, a totalizing counter, a rocker lever upon said shaft for each of said individual counters and adapted to be operated by the said pawl thereof, a similar pawl for operating the said totalizing counter and 25 a separate rocker lever upon said shaft for operating the pawl of the said totalizing counter upon the operation of any of the pawls of the other individual counters.

2. A counting machine of the character described comprising a plurality of individual counters, each of said counters comprising a base, a plurality of numbered wheels rotatable upon a shaft mounted on said base, one of said wheels comprising a units wheel, teeth associated with 40 said units wheel, a pawl rotatable upon a separate shaft on said base and adapted to engage said teeth for rotating the said units wheel the distance of one tooth for each cycle of operation of said pawl, a manually operated member mounted 45 upon a separate shaft on said base for operating said pawl; the said totalizing counter comprising similar number wheels, units wheel and pawl, all of said individual counters and totalizing counter being secured in side by side relation 50 to form a multiple counter unit and having a common rocker shaft extending through all of said counters, a lever on said rocker shaft in each of said counters for rotating the said shaft upon 55 the operation of any of said pawls, and a similar lever on said shaft in the totalizing counter but mounted on said shaft in reversed position with relation to the other levers on said shaft for operating the pawl of the said totalizing counter 60 through the rotation of said rocker shaft by the action of any of the other pawls of the individual counters upon the rocker arms associated therewith and thereby causing operation of said totalizing counter through the operation of either of 65 the others of said individual counters.

3. For a counting machine of the character described; the combination comprising a plurality of individual counters; each of said counters comprising a separate base and a registering mechanism mounted thereon and having an actuating member and means for manually operating said actuating member, a separate counter comprising a separate base and a separate registering mechanism having an actuating member therein simi- 75

lar to the actuating member of each of the said individual counters, a common shaft extending through all of said counters and rotatably mounted in each of the bases of said individual counters, means in connection with the actuating member of each of said individual counters for rotating said shaft, and similar means in reversed position on said shaft for operating said separate counter through the rotation of said shaft upon the operation of one of said individual counters.

10 4. A counting machine of the character described comprising a plurality of individual counters; each comprising a series of registering

wheels mounted upon separate shafts, a pawl for rotating said wheels, an actuating member comprising a pinion for actuating said pawl, manually operated means comprising a gear portion in mesh with said pinion for rotating said actuating member, a common rotatable shaft extending through all of said individual counters, means in each of said individual counters for rotating said shaft by the actuating member in each of said counters, a separate counter, and a similar actuating member therein operable by the rotation of said common shaft.

ANTON VAN VEEN.
